UNITED STATES PATENT OFFICE.

JOSEPH LOEB, OF PHILADELPHIA, PENNSYLVANIA.

DESIGN FOR FRINGE.

SPECIFICATION forming part of Design No. 13,588, dated February 6, 1883.

Application filed December 16, 1882. Term of patent 3½ years.

To all whom it may concern:

Be it known that I, JOSEPH LOEB, a citizen of the United States, residing in the city and county of Philadelphia, State of Pennsylvania, 5 have invented and produced a new and original Design for Fringe, of which the following is a specification, reference being had to the accompanying drawing, forming part thereof.

The accompanying drawing is a face view 10 of a section of fringe embodying and illustrating my design, which consists of a fringe having a heading, A, of any suitable kind, to which are attached at intervals chenille pendants B. The middle portion, a, of each pendant is 15 formed of a plain block, so as to present throughout the length of the fringe a broad band, C. The portions b b' of each pendant, respectively above and below the middle portion, a, are formed of blocks or stripes of different colors, thus presenting throughout the 20 length of the fringe upper and lower striped bands, D, or a striped band on opposite ends of the middle plain band, C. The block a and striped portions b b' of each pendant are of 25 uniform diameter.

The end tips, c, may or may not form parts of the design.

I do not confine myself to the use of any given colors or material.

I claim—

1. A design for a fringe, consisting of a heading and a series of chenille pendants, each of which has at its middle a plain block, a, and top and bottom portions of uniform diameters presenting throughout the length of the fringe, 30 at the middle thereof, a plain band, C, substantially as set forth. 35

2. A design for a fringe, consisting of a heading and a series of chenille pendants, each of which has a plain block at the middle, and 40 striped blocks at the upper and lower ends thereof, presenting throughout the length of the fringe a plain band at the center, and striped bands, respectively, above and below the central band, substantially as set forth.

JOSEPH LOEB.
